INVENTOR.

Henry C. Pfister:

BY
Geo. P. Kinscher
ATTORNEY.

UNITED STATES PATENT OFFICE.

HENRY C. PFISTER, OF GREAT FALLS, MONTANA.

ARCH SUPPORT.

Application filed September 18, 1922. Serial No. 588,859.

To all whom it may concern:

Be it known that I, HENRY C. PFISTER, a citizen of the United States, residing at Great Falls, in the county of Cascade and State of Montana, have invented certain new and useful Improvements in Arch Supports, of which the following is a specification.

This invention relates to an arch supporter, and has for its object to provide a device of such class, in a manner as hereinafter set forth, with means for obtaining a positive support and brace for the metatarsal bones at the arch of the human foot, and whereby the arch supporter will not only brace and hold in place in a transverse direction the metatarsal bones of the arch, but will furthermore support the same longitudinally, under such conditions serving to eliminate the source and cause of the major portion of foot trouble in connection with the human feet.

Further objects of the invention are to provide an arch supporter which is simple in its construction and arrangement, strong, durable, compact, efficient and convenient in its use, readily set up, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a longitudinal sectional view of a shoe illustrating a foot therein, and further showing an arch supporter in accordance with this invention and illustrating the supporter in position on the foot.

Figure 2 is a longitudinal sectional view of an arch supporter in accordance with this invention.

Figure 3 is an inverted plan view thereof.

Referring to the drawings in detail, 1 denotes a shoe and 2 the representation of the human foot extended within the shoe.

An arch supporter, in accordance with this

invention comprises a circular elastic band 3, which is adapted to be mounted on the foot 2, and which is adapted to hold in position, the metatarsal bones of the foot 2, in a transverse direction.

Extended into the band 3, is a sole member formed of any suitable flexible material and including a contracted rear portion 4, and an enlarged front portion 5. The contracted rear portion 4, is extended into the band 3, as well as being secured therewith by a row of stitching 6, the contracted rear portion 4, projects slightly beyond the rear end of the band 3, as indicated at 7. Attached to the lower face, of the enlarged or forward portion 5, of the sole member, 65 is a semi-oval shape pocket forming member 8, and which has its outer edge secured to the sole member by a row of stitching 9. The rear edge 10 of the member 8, is disconnected from the sole member and forms 70 in connection with the latter a pocket 11, in which is mounted a cushion forming pad 12, which is elliptical in cross section, as well as being circular in contour. When the pad 12, is mounted in the pocket 11, the 75 sole member 8 is extended, forming a concave support, and the sole member is also extended to provide a convex support, and the pad 12, in connection with the sole member and pocket forming member 8, when 80 arranged in operative position, support the metatarsal bones in a longitudinal direction.

Although the pad 12, is illustrated as circular in contour, it is to be understood however, that various sizes and forms thereof, 85 can be employed, furthermore, varying lengths of sole members and diameters of bands can also be employed, depending upon the length and width of the foot to which the supporter is to be applied.

The supporter is constructed and designed and patterned in such a manner as to provide for the use thereof in connection with the right and left feet and may be constructed of any suitable flexible and form-fitting material desirable for the purpose intended.

It is furthermore to be understood that the supporter is extremely light in weight, as well as compact, thus overcoming any 105 awkwardness with respect thereto, and the elements thereof so designed that it may be carefully fitted and formed especially to fit

various types of feet, in an accurate manner, to assure absolute efficiency for the purpose intended thereby.

What I claim is:

5. 1. An arch supporter comprising a flexible sole member formed with a contracted rear portion and an enlarged forward portion, an upright resilient band connected to the contracted rear portion of said sole member, means to provide on the lower face of the enlarged portion of said sole member a pocket opening rearwardly, and a cushioning element mounted in said pocket and of a contour to provide said sole member with convex supporting surfaces.
10. 2. An arch supporter comprising a flexible sole member, a resilient band connected to and projecting upwardly from the rear of said member, and a removable cushioning element extended into the lower face at the forward portion of said sole member and providing the latter with convex supporting surfaces.
15. 3. An arch supporter comprising an upright resilient band, a sole member secured to the lower portion thereof and projecting forwardly therefrom, and a cushioning element extended into the lower face of said sole member and positioned forwardly with respect to said band and of a contour to provide said sole member with convex supporting surfaces.
20. 4. An arch supporter comprising a resilient band, a sole member connected thereto and projecting forwardly therefrom and provided on its under face near its forward end with a pocket opening rearwardly, and a forwardly projecting cushioning element removably mounted in said pocket and substantially elliptical in cross section.
25. 5. An arch supporter comprising a resilient band, a sole member connected thereto and projecting therefrom, a pocket forming member secured to the lower face of said sole member forwardly with respect to said band and providing in connection with said member a pocket opening rearwardly with respect thereto, and a pad removably mounted in said pocket and providing in connection with the said member convex supporting surfaces.
30. 6. An arch supporter comprising a resilient band, a sole member connected thereto and projecting upwardly with respect to said band and providing in connection with said member a pocket opening rearwardly with respect thereto, and a pad removably mounted in said pocket and providing in connection with the said member convex supporting surfaces, said pad being elliptical in cross section.
35. 7. An arch supporter comprising a sole member, a resilient band connected to and extending transversely with respect to the lower face of the rear portion of said sole member and projecting upwardly therefrom, means to provide the lower face of the sole member at the forward portion thereof with a rearwardly opening pocket, and a cushioning element mounted in said pocket and extending against the lower face of said sole member and constituting means to provide convex supporting surfaces.
40. 8. An arch supporter comprising a sole member having a contracted rear portion and an enlarged forward portion, a resilient band connected to and extending transversely with respect to the lower face of the contracted portion of said sole member and projecting upwardly therefrom, means secured to the lower face of the enlarged forward portion of said sole member to provide in connection therewith a rearwardly opening pocket, and a cushioning element mounted in said pocket and extending against the lower face of said sole member and constituting means to provide convex supporting surfaces.

In testimony whereof, I affix my signature hereto.

HENRY C. PFISTER.
